UNITED STATES PATENT OFFICE

118,439

DESIGN FOR A STOCKING OR SIMILAR ARTICLE

Clarke W. Tobin, South Orange, N. J., assignor to Propper-McCallum Hosiery Co. Inc., New York, N. Y., a corporation of Delaware

Application March 16, 1939, Serial No. 83,607

Term of patent 14 years

To all whom it may concern:

Be it known that I, Clarke W. Tobin, a citizen of the United States, residing at South Orange, in the county of Essex and State of New Jersey, have invented a new, original, and ornamental Design for a Stocking or Similar Article, of which the following is a specification, reference being had to the accompanying drawings, forming part thereof.

of the stocking shown in Figure 1, on an enlarged scale; and

Fig. 3 is an enlarged view of a fragmentary part of the heel portion of the stocking.

The design is characterized by the application of the lace-like elements on the heel portion of the stocking as shown.

I claim:

The ornamental design for a stocking or similar article, as shown and described.

CLARKE W. TOBIN.
